Primary Examiner — Vy N Koenig*Assistant Examiner* — Qiawen W Wiechert(74) *Attorney, Agent, or Firm* — Birchwood IP(57) **CLAIM**

The ornamental design for a pillow, as shown and described.

DESCRIPTION

FIG. 1 is a first perspective view of a pillow showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion 9 in FIG. 2.

The short dash-long dash broken lines used in FIGS. 2 and 9 illustrate the boundaries of the enlarged detailed view and form no part of the claimed design.

1 Claim, 9 Drawing Sheets(56)
